UNITED STATES PATENT OFFICE.

ROLAND F. SCHROEDER AND LOUIS S. SAKOLS, OF MILWAUKEE, WISCONSIN.

DESIGN FOR AN INCENSE BURNER.

Application filed January 6, 1926. Serial No. 15,960. Term of patent 7 years.

To all whom it may concern:

Be it known that we, ROLAND F. SCHROEDER and LOUIS S. SAKOLS, citizens of the United States, residing at Milwaukee, in the county of Milwaukee and State of Wisconsin, have invented a certain new and original and ornamental Design for Incense Burners, of which the following is a specification.

Reference is here made to the accompanying drawings which form part of the specification:

Figure 1 of the drawings is a front elevation of an incense burner constituting my new design.

Figure 2 is a left side elevation thereof.

We claim:

The ornamental design for an incense burner, as shown.

In testimony whereof we affix our signatures.

ROLAND F. SCHROEDER.
LOUIS S. SAKOLS.
